Inventor:
JOHN F. RUTH,
By John N. Bruninger
His Attorney.

UNITED STATES PATENT OFFICE.

JOHN F. RUTH, OF ST. LOUIS, MISSOURI.

METAL WINDOW.

Application filed October 22, 1927. Serial No. 227,968.

This invention relates to windows and more particularly to metal windows.

One of the objects of this invention is to provide a metal window construction, in which a weatherstrip adapted to seal the side opening between the sash and the jamb may be applied in a simple and effective manner.

Another object is to provide such a construction, in which the sash will be resiliently held against rattling.

Another object is to provide a construction in which such weatherstripping may be applied in such a manner as to be easily removable.

Another object is to provide a simple construction, which will be economical to manufacture and easy to install.

Further objects will appear from the following description, taken in connection with the accompanying drawing, in which—

Figure 1 is a detail, in vertical section, of a window embodying this invention; and

Figure 2 is a horizontal section on line 25 2—2 of Figure 1.

Referring to the drawing, 1 designates a window jamb, which may be constructed of sheet metal or other suitable material, in box section, as shown in Figure 2, so as to provide a housing for the sash weights 2. Mounted on the inner face of the jamb 1 is an auxiliary jamb 3. This auxiliary jamb is preferably constructed with an outstanding central portion connected by angular flanges 4 to side flanges 5, which in turn terminate in lateral flanges 6 engaging the inner face of the jamb 1 and secured thereto by means of screws 7 or other suitable fastenings. Mounted on the jamb 1 are outside and inside plates 8 and 9, respectively, secured to the jamb 1, by means of screws 10, rivets 11, or other suitable fastenings. The plates 8 and 9 provide outer and inner guiding flanges 12 and 13, respectively, adapted to guide the upper and lower sash 14 and 15.

Mounted on the auxiliary jamb 3, by means of rivets 16 or other suitable fastenings, is a parting stile 17. The stile 17 may be constructed of sheet metal bent back upon itself so as to form guiding flanges 18 adapted to engage the guide flanges 19 of the sash 14 and 15 to guide the latter in their up and down movement. After the bends forming the flanges 18, the metal is bent back to provide flanges 20. The flanges

20 are spaced from the walls of the auxiliary jamb 3 so as to permit the insertion therebetween of the flange 21 of a strip 22 of resilient material, preferably sheet metal.

The strip 22 is bent outwardly for a portion of its width so as to lie against the flange 4 of the auxiliary jamb and is then looped back so as to provide a resilient flange 23 adapted to bear against the edge of the flange 19, as shown in Figure 2. This strip, therefore, not only provides a weather seal to keep drafts from passing around the flange 19 from the outside to the inside of the window, but also bears yieldingly against the edge of the sash so as to keep the same centered and to press the same yieldingly against the guiding flanges of the jamb. This keeps the sash at all times firmly pressed against its guiding flange so as to keep it from rattling.

The strip 22 may be applied to the parting stile by inserting the flange 21 between the flange 20 and the auxiliary jamb, the insertion being made from the end of the jamb. Suitable stops 24, secured to the auxiliary jamb or the flange 20, may be placed at proper points therewith so as to prevent the insertion of the strip 22 too far and in order to properly position the same. The strip 22 thus inserted is interlocked with the parting stile so as to be permanently held in assembled relation thereto and in a position to properly engage the flange 19 of the sash.

It will be seen, therefore, that this invention provides a window construction which is not only cheap to manufacture, but which is very effective in service. The auxiliary jamb 3 has spaced bearing points against the jamb 1 at the flanges 6. This jamb may be adjusted relatively to the sash by means of the bolt 25, of which there may be any number. With the auxiliary jamb adjusted to give the proper clearance between the guide flanges, the strip 22 keeps the sash under a yielding tension so as to prevent rattling and at the same time provides an effective weather-seal. This strip is placed in a location where it is protected from the weather and where it is not subject to contact by anyone handling the window. Once in place, therefore, it will be undisturbed throughout its life. In case of wearing out of this strip, it is easily replaced by dismounting the auxiliary jamb and simply inserting a new strip. The cost of repairs

is thus reduced to a minimum. The parting stile itself is also easily removable in case of excessive wear.

It is obvious that various changes may be made, within the scope of the appended claims, in the details of construction without departing from the spirit of this invention; it is, therefore, to be understood that this invention is not limited to the specific details shown and described.

Having thus described the invention, what is claimed is:

1. In a metal window having a sash, a jamb and a parting stile therealong, a loose strip of resilient material interlocked with the stile and pressing yieldingly against the edge of the sash.

2. In a metal window having a sash, a jamb and a parting stile therealong, a continuous strip of resilient material extending along the stile and pressing yieldingly against the edge of the sash.

3. In a metal window having a sash, a jamb and a parting stile therealong, a loose strip of resilient material extending along and interlocked with the stile and pressing yieldingly against the edge of the sash.

4. In a metal window having a sash provided with a guide flange and a parting stile engaging said flange, a continuous strip of resilient material extending along the stile and pressing yieldingly against the edge of said flange.

5. In a metal window having a jamb and a sash having a guide flange, an auxiliary jamb, a parting stile on said auxiliary jamb, and a resilient strip confined between said auxiliary jamb and said stile and bearing against the edge of the guide flange.

6. In a metal window having a sash, an auxiliary jamb, a parting stile formed of sheet metal bent back upon itself to provide a guiding flange for the sash and having a flange spaced from said jamb, and a strip of resilient material interlocked with said flange and bearing against the edge of the sash.

7. In a metal window having a sash, an auxiliary jamb, a parting stile formed of sheet metal bent back upon itself to provide a guiding flange for the sash and having a flange spaced from said jamb, and a strip of resilient material confined between said latter flange and said jamb and bearing against the edge of the sash.

8. In a metal window having a sash, an auxiliary jamb, a parting stile mounted thereon and having a flange spaced therefrom, and a strip of resilient material insertable between said flange and said jamb so as to bear against the edge of the sash.

9. In a metal window having a sash, an adjustable auxiliary jamb, a parting stile thereon having a guiding flange adapted to engage the sash, and a loose strip of resilient material interlocked with said stile and pressing yieldingly against the edge of said sash.

10. In a metal window having a sash, an adjustable auxiliary jamb, a parting stile thereon having a guiding flange adapted to engage the sash, and a loose strip of resilient material confined between said auxiliary jamb and said stile and pressing yieldingly against the edge of said sash.

In testimony whereof I affix my signature this 15th day of October, 1927.

JOHN F. RUTH.
